US00D886320S

(12) **United States Design Patent** (10) **Patent No.:** **US D886,320 S**
(45) **Date of Patent:** **** Jun. 2, 2020**

(54) **FLUID SEQUESTRATION APPARATUS**

(71) Applicant: **Wavesense, Inc.**, Irvine, CA (US)

(72) Inventors: **Timothy M. Bruemmer**, Carmel, IN (US); **Bruce D. Irvine**, Concord, CA (US); **Christopher Feistel**, Laguna Beach, CA (US)

(73) Assignee: **WAVESENSE, INC.**, Irvine, CA (US)

(**) Term: **15 Years**

(21) Appl. No.: **29/689,376**

(22) Filed: **Apr. 29, 2019**

(51) LOC (12) Cl. **24-01**

(52) U.S. Cl.

(57) **CLAIM**

The ornamental design for a fluid sequestration apparatus, as shown and described.

DESCRIPTION

FIG. 1 is an elevated perspective view showing our new design with an interconnected fluid reservoir and positioned to co-axially engage with a magnetic housing wherein the fluid reservoir and magnetic housing are disclosed in broken lines to illustrate an environment;

FIG. 2 is an elevated perspective view thereof;

FIG. 3 is a front view thereof;

FIG. 4 is a left side view thereof;

FIG. 5 is a top view thereof; and,

FIG. 6 is a bottom view thereof.
